UNITED STATES PATENT OFFICE.

GORDON M. PROUDFOOT, OF CHICAGO, ILLINOIS, ASSIGNOR TO CRUVER MANUFACTURING COMPANY, OF CHICAGO, ILLINOIS, A CORPORATION OF ILLINOIS.

CASING FOR MECHANISMS.

Application filed August 1, 1924. Serial No. 729,483.

This invention relates to housings for radio condensers and other mechanisms, including a, preferably, transparent portion, wherein said transparent portion may be 5 easily removed and replaced without requiring disassembling of the housing or the removal or manipulation of any fastening or retaining devices for said transparent portion and wherein the latter consists of 10 a flexible substance, such as sheet-celluloid incapable of being splintered and thus causing particles thereof to become lodged in the mechanism housed thereby and which, at the same time is so associated with permanent housing elements as to provide a 15 substantially dust proof casing for the said mechanism.

The preferred embodiment of the invention is illustrated in the accompanying 20 drawings, wherein:

Fig. 1 is a perspective view of a radio condenser (as exemplary of a mechanism) equipped with a housing constructed in accordance with the invention.

Fig. 2 is a transverse section of the same.

Fig. 3 is a fragmentary radial section of the same on the line 3—3 of Fig. 2.

Figs. 4 and 5 are, respectively, a fragmentary plan view and side elevation of the 30 flexible, transparent element of the housing.

The invention relates more particularly to housing which include a peripheral or circumferential wall or wall portion bordered by end-plates or other permanent 35 parts of the mechanism per se or constitute housing elements more or less permanently associated with the mechanism.

In the instance illustrated, the mechanism consists of a radio-condenser substantially 40 identical with that illustrated and described in my pending application for United States Letters Patent, Serial No. 695,889, filed February 29, 1924, but may be also applied, for example, to spring or other instruments 45 of precision of various types.

In the instance illustrated, the mechanism or its housing, includes two circular end plates A provided in their opposed faces with annular grooves B disposed closely 50 contiguous to and concentric with their peripheral or circumferential edges. Said plates are suitably permanently spaced from each other and are usually, as in the instance illustrated, parallel.

55 The transparent housing element consists

of a strip C of a flexible material, such as sheet celluloid, of a width substantially equal to the distance between the bottoms of the grooves B of the plates A and of a length somewhat in excess of the circumferential 60 or peripheral length of said grooves, one extreme end portion of said strip C suitably permanently rendered concavo-convex, as at D, the convex face of said portion being a part of the outer or exposed face of the 65 strip C when engaged along its side edges in the grooves B. The strip C is normally straight and is, as indicated in dotted lines in Fig. 3, slightly bowed transversely preparatory to starting the side edges of the 70 end thereof opposite to the end-portion D, into the grooves B, said bowing being temporarily digitally effected to first decrease the spacing of said side edges of said strip to slightly less than the distance between 75 the opposed faces of the plates A. This bowing of the strip C is gradually continued throughout the length thereof simultaneously with effecting digital curving thereof to thereby gradually continuously effect a 80 springing of its side edge portions into said grooves B, the latter being preferably of a width substantially double the thickness of the sheet C.

The end-portion D is adapted to overlap 85 the other end portion of the strip C, as shown in Fig. 2, and, to effect insertion of the side edges of said portion D into the grooves B it is necessary to digitally flatten out the same, this being digitally accomplished and subsequently maintained by said 90 grooves. The end terminals of said portion D, as well as the lengthwise edge thereof, are thus maintained in firm contact with the outer face of the other end portion 95 of the strip C by the frictional engagement of the outer faces of the end terminals of the portion D with the outer walls of the grooves B, and thus serves to produce a substantially sealed joint at this point.

The strip C is easily removed by insertion of a finger-nail or knife-edge under the last mentioned or overlapping end thereof and just pulling the strip away in the same manner as adhesive tape is unwound from 105 a roll and may be removed and replaced as often as necessary or desirable without injury thereto.

Obviously other materials, such as paper, for example, may be substituted for the cel- 110

luloid if transparency is not required and it is desired to reduce expense.

I claim as my invention:

5 A casing for the purpose set forth comprising a pair of end plates suitably connected together, spaced from each other and each having its inner face formed with an annular groove in proximity to its edge, and a removable flexible strip forming the
10 body portion of the casing and of a width greater than the space between said plates, said strip adapted to be bowed between its side edges progressively to provide for the
15 progressive springing of its side edges from its end into said grooves to form the strip of

annular contour with the end terminal portions thereof overlapping, each of said grooves of a width substantially twice the thickness of said strip, the outer overlapping end terminal portion of said strip bowed 20 transversely and having the end terminal portions thereof frictionally engaging with the outer walls of said grooves to produce a substantially sealed joint between the lengthwise edge of said bowed portion and the 25 body of the strip, said bowed portion further providing means to permit of the removal of the strip from said end plates.

GORDON M. PROUDFOOT.
